UNITED STATES PATENT OFFICE

WILLIBALD LOEBCKE, OF PRETTIN, KREIS TORGAU, GERMANY, ASSIGNOR TO A. H. REUPKE, OF CHICAGO, ILLINOIS.

PROCESS OF PRINTING.

Application filed June 29, 1923. Serial No. 648,442.

To all whom it may concern:

Be it known that I, WILLIBALD LOEBCKE, a citizen of Germany, and a resident of Prettin, Kreis Torgau, Province of Saxony, 5 Prussia, Germany, have invented a new and useful Improvement in Processes of Printing, of which the following is a specification.

This invention relates to the art of printing.

10 The main objects of this invention are to provide an improved and inexpensive method of printing for effecting the result produced by the well known process of reverse etching, wherein the design or legend remains the color of the sheet and appears on a printed background; and to provide a method of printing show-cards, signs, price tickets, and the like by a person unskilled in the art of printing.

20 One form of apparatus adapted for carrying out this invention is shown in the accompanying drawings, wherein:

Figure 1 is a plan of the apparatus, including an elastic plate and its supporting block, the pressure roller being shown in perspective.

Fig. 2 is a vertical, longitudinal section of the same.

Fig. 3 is a plan of the apparatus, showing 30 the method of arranging the cutouts thereon.

Fig. 4 is a plan of the apparatus showing a printed sheet being removed from the plate and cutouts after the printing operation.

Fig. 5 is a plan of the printed sheet.

The process of reverse etching which is now in use for producing designs and letters upon a printed background while leaving the design the color of the sheet is expensive and also requires a high degree of skill in its performance.

40 The apparatus for carrying out the present invention is inexpensive and the method is simple, so that it may be readily accomplished without particular skill in the art of printing.

This invention involves an improved process of printing, which consists in placing 50 a series of cutouts, making up the desired design or legend, on an inked pad or elastic plate. The letters or figures are inverted and arranged upon the pad in reverse order. The sheet to be printed is then placed upon the pad over the cutouts and pressure is

applied to the back of the sheet, so as to transfer to the face thereof ink on the pad surrounding the cutouts. If desired, several prints may be made before it is necessary to remove the cutouts for replenishing 60 the ink on the pad. The present method of printing is particularly suitable for producing transparent cards used in illuminated signs for advertising purposes.

In the form shown, the apparatus for carrying out this invention includes an elastic plate or pad 1, mounted on a block 2, of a base 3. The supporting base 3 projects beyond the edges of the pad so as to form a ledge 4, on which appears a suitable scale, 70 as shown at 5.

The cutouts are made of paper or other suitable thin material, and are preferably handled by a suitable form of tweezers 6, as shown in Fig. 3. In the form shown, the 75 cutouts include letters 7, and a rectangular border strip 8.

To facilitate the proper placing of the cutouts upon the pad 1, a straight edge 9 extends across the pad, and is provided with 80 lugs 10, arranged for sliding engagement with the end ledges 4. The lugs 10 are arranged so as to space the straight edge slightly away from the pad 1. The upper face of the straight edge is provided with 85 a longitudinally extending recess forming a seat 11 for the cutouts.

In operation, ink is applied to the pad 1 by suitable means, such as a roller 12. The cutouts are then placed in an inverted position upon the inked pad in reverse order, 90 as shown in Fig. 3. The straight edge 9 is then removed from the apparatus, and the sheet 13 to be printed is placed down over the pad and cutouts, and pressure is applied 95 to the back of the sheet by suitable means, such as a roller, not shown. The pressure of the roller transfers to the face of the sheet 13 ink on the pad 1 surrounding the cutouts, so that the design or legend remains the 100 color of the sheet and appears on a printed background.

Although but one specific method of following out this process is herein described, it will be understood that steps thereof may 105 be modified or altered without departing from the spirit of this invention as defined by the following claims.

I claim:

1. The process of printing which consists 110

in inking a pad, placing thereon a cutout, then placing a sheet upon the pad and cutout and applying pressure to the back of the sheet to transfer to the face thereof ink on the pad surrounding said cutout, and then removing the sheet from the pad and cutout.

5. The process of printing which consists in inking a pad, placing thereon a plurality of separately formed cutouts arranged to form a predetermined legend, then placing a sheet upon the pad and cutouts and applying pressure to the back of the sheet to transfer to the face thereof ink on the pad surrounding said cutouts, and then removing the sheet from the pad and cutouts.

10. Signed at Leipzig, Germany, this 29th day of May 1923.

WILLIBALD LÖBCKE.
